(57) **CLAIM**

The ornamental design for a pipe hanger, as shown and
described.

DESCRIPTION

FIG. 1 is a perspective view of a pipe hanger showing my
new design;

FIG. 2 is a front elevational view thereof;

FIG. 3 is a top plan view thereof;

FIG. 4 is a right side elevational view thereof;

FIG. 5 is a bottom plan view thereof;

FIG. 6 is a rear elevational view thereof; and,

FIG. 7 is a left side elevational view thereof.

The broken lines immediately adjacent the shaded areas
represent the bounds of the claim and all other broken lines
are for illustrative purposes only. None of the broken lines
form a part of the claimed design.

1 Claim, 4 Drawing Sheets

FIG. 2.

FIG. 3.

FIG. 4.

FIG. 5.
